B. BOLEY.
CASE FOR DEMIJOHNS.
APPLICATION FILED APR. 12, 1915.

Patented Nov. 30, 1915.

UNITED STATES PATENT OFFICE.

BENJAMIN BOLEY, OF NEW YORK, N. Y.

CASE FOR DEMIJOHNS.

1,162,444.

Specification of Letters Patent.

Patented Nov. 30, 1915.

Application filed April 12, 1915. Serial No. 20,726.

To all whom it may concern:

Be it known that I, BENJAMIN BOLEY, a citizen of the United States, residing at New York, county of New York, and State 5 of New York, have invented new and useful Improvements in Cases for Demijohns, of which the following is a specification.

This invention relates to a packing case which is essentially adapted for securely 10 holding a demijohn or similar bottle against breakage when handled, transported or shipped.

The invention is primarily designed to prevent fraudulent withdrawal of the liquid 15 contained in the bottle or tampering with the case after it has been sealed for transportation.

The object of the invention is to provide a case of strong construction wherein the 20 bottle is secured in a peculiar way so as to prevent removal of the same without damaging the case beyond repair or detection. The case is particularly utilized for transporting liquids requiring a revenue stamp, 25 and it is provided with easily manipulated means coacting with the mouth and neck of the bottle whereby the contents are sealed.

The novel features of the invention are 30 more fully described in the following specification and claims, and illustrated in the accompanying drawing in which:

Figure 1 represents a perspective view of a case embodying this invention. Fig. 2 is a vertical transverse section of the same. 35 Fig. 3 is a vertical longitudinal section of the same. Fig. 4 is a perspective view of a slide. Fig. 5 is a perspective view of a shelf or support.

In this drawing is shown a packing case 40 consisting of sides *a*, end boards *b* and bottom *c* built up of a number of sections. The side, end and bottom boards are spaced at *d* to admit light into the case for observing the interior of the bottle. These boards are 45 secured to a series of vertically disposed posts *e* each post being located at the corner of the interior of the case. The upper portion of the case is provided with a top *f* formed by shelving or slanting the upper 50 sides of the case. The top has an opening or slot *g* to give access to the neck of a bottle *h* disposed in the case. The case is made to approximately fit the contour of a bottle which is placed in the case before the top boards are secured.

A slotted bifurcated support or shelf *i*

is secured in the top portion of the case. This support by reason of the keyhole shape of its slot engages the neck of the bottle below a shoulder *j* situated at the upper end 60 of the bottle. The support locks or securely fastens the bottle into the case, preventing it from being removed and also eliminating movement of the neck, when the case is jarred.

A sheet metal slide *k* is arranged in the top of the case to coact with the mouth and neck of the bottle. The slide has runners *m* formed by bending the lower sides of the slide inwardly to support the slide on 70 the shelf. The slide fits snugly in the case and it is operated to move in a rectilinear path along the shelf to cover or uncover the mouth of the bottle. The slide is provided with an eye *n* which when the slide 75 covers the neck of the bottle will register with a similar eye *o* secured to the upper end of the slot. When the slide is in this position a seal *p* coacting with the eye will effectively lock the slide to the case. It will 80 be seen that the eye *n* limits the movement of the slide in either direction relative to the slot.

As shown in the drawing the lower side portions of the case are provided with metal 85 straps *q* extending along the bottom and fastened to the case. These strap members in conjunction with cleats *r* reinforce the case and prevent the bottom from being removed without fracturing the case. The 90 cleats also form supports for taking up any shocks given to the case when it is set down. A buffer spring *s* is secured to each of the posts *e* for engagement with the bottle so as to take up lateral concussions 95 given to the case.

It will be seen that the slide and its dependent parts are housed in the top recess of the case so as to obviate any projecting parts outside of the case to minimize damage to the parts.

I claim:

1. A packing case adapted to contain a demijohn and having an opening at the top, a support secured in the case, and a shield 105 slidably arranged in the opening coacting with the support to cover the neck of the demijohn.

2. A packing case adapted to contain a demijohn and having an opening at the top, 110 a support secured in the case below the opening, a shield slidably arranged in the open-

ing on the support to cover the neck of the demijohn, and means for sealing the shield.

3. A packing case adapted to hold a demijohn and having an opening at the top, a support engaging the neck of the demijohn for securing it in the case, and a shield slidably mounted on the support for covering the neck of the demijohn.

4. A packing case adapted to hold a demijohn and having an opening at the top, a bifurcated support to engage the neck of

the demijohn, and a shield slidably arranged on the support for covering the neck and mouth of the demijohn.

In testimony whereof I have hereunto set my hand in the presence of two subscribing witnesses.

BENJAMIN BOLEY.

Witnesses:

CHRISTIAN H. ALMSTAEDT,
HAZEL V. REIDENBACH.
